UNITED STATES PATENT OFFICE.

WILLIAM L. DUTCHER, OF ROME, NEW YORK.

BOLT-CUTTER.

SPECIFICATION forming part of Letters Patent No. 448,324, dated March 17, 1891.

Application filed November 12, 1890. Serial No. 371,157. (No model.) Patented in Canada March 17, 1890, No. 33,945.

To all whom it may concern:

Be it known that I, WILLIAM L. DUTCHER, of Rome, in the county of Oneida and State of New York, have invented certain new and useful Improvements in Bolt-Cutters, (for which Letters Patent of the Dominion of Canada, No. 33,945, dated March 17, 1890, were granted to William L. Dutcher and Moses M. Davis;) and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

My invention relates to an improved bolt-cutter.

In the drawings which accompany and form a part of this specification, and in which similar letters and figures of reference refer to corresponding parts in the several figures, Figure 1 shows my improved bolt-cutter, the jaws being open or partially so. Fig. 2 shows the same in closed position. Fig. 3 shows the jaws on a larger scale than that of Figs. 1 and 2 and an end view of the same as seen from the left. Fig. 4 shows an end view of each of the operating-lever handles separated and also together. Figs. 5 and 6 show portions of the operating-lever handles. Fig. 7 shows adjusting-blocks used in the device. Fig. 8 shows a bearing-pin used in the cutter.

Reference being had more specifically to the reference-numerals marked on the drawings, 1 and 1^a are the lever-handles pivoted to each other and to the cutting-jaws 2 and 2^a. The cutting-jaws 2 and 2^a are provided with straps 3 upon either side, as shown in Fig. 3, and are pivoted in the straps at 5 and 6. The jaws 2 and 2^a are each provided with a semicircular recess, which together are adapted to receive cylindrical bearing-pin *n*, which when in position prevent lateral movement of the jaws 2 and 2^a with reference to each other. The handle-lever 1 has a pair of ears 4, adapted to receive the projecting portion 5 of handle-lever 1^a. The projecting portion 5^a of the handle is recessed to receive the adjusting-block 6. With each pair

of cutters I provide a series of adjusting-blocks, as shown at Fig. 7, having recess *x*, adapted to engage upon projection 7 of the lever-handle and prevent rotation of the block. 55 In the block is provided an opening *y* for the pivotal pin between the lever-handles, and in the several blocks the pivotal pin is located substantially in the center, as shown in the lower portion of Fig. 7, or adjacent to the recess or cut-away part *x*, as shown in the middle portion of Fig. 7, or on the opposite side of the block, as shown in the upper portion of Fig. 7. The block, together with the projecting portion 5 of the handle 1^a, is received 60 between the ears 4 of the lever-handle 1, and the pivotal pin is inserted through the opening *z* in the ears 4 and *y* in the adjusting-block. On either side of the ears 4 and mounted on the pivotal pin between the lever-handles are washer-plates *a a*, Fig. 4, of 65 larger diameter than the ear 4, and are adapted to close the space between the edge of the ears 4 and a similar recess in the side of the lever on each side of the projection 5 and prevent foreign substances entering the space that would otherwise be left in securing the 70 several adjustments hereinafter explained. A buffer 10 is provided upon one of the handles mounted upon adjusting-screw, whereby 75 the movements of the handles together to close the jaws can be limited.

With each pair of tongs I provide several adjusting-blocks, as shown in Fig. 7, and when the tongs are new the adjusting-block 85 having the pivotal opening nearest to the recess *x* is used and the adjusting-screw 10 is in its most projected position. As the tongs become worn from use, the screw 10 is screwed farther into the handle, allowing the edges to 80 come together until the limit of adjustment by the screw 10 is reached, when the tongs are taken apart at the pivotal point between the lever-handles 1 and 1^a, and the block having the pivotal opening farther from the recess *x* is substituted for the one theretofore in use, and the screw 10 is again run out to 90 its most projected position, when the tongs will be found to have their jaws completely closed when the lever-handles are closed. 95 They are then used in this way until the jaws become so worn as to necessitate the use of 100

another adjusting-block, having pivotal point still farther from the recess x in the side thereof.

It is evident that instead of the projection 5 7 a pin might be used entering an opening, as x , in the side of the adjusting-block and a similar one in the side of the lever-handle 1^a , and that other alterations and changes in and from the construction described may be made 10 without departing from the spirit of my invention.

What I claim as new, and desire to secure by Letters Patent, is—

1. The combination, in a bolt-cutter, of the 15 cutting-levers pivoted in straps and having a semicircular recess in each between the straps, a cylindrical bearing-pin adapted to enter the recesses and prevent lateral movement of the jaws with reference to each other, 20 and the operating-lever handles pivoted to each other and to the ends of the cutting-jaws, substantially as set forth.

2. The combination, with a bolt-cutter, of the cutting-levers pivoted in straps engaging 25 upon either side thereof, the semicircular recess in each jaw substantially in line between the pivotal points of the cutting-levers, the bearing-pin within the semicircular recess for preventing lateral movement of the 30 jaws with reference to each other, the operating-lever handles pivoted to each other and to the ends of the cutting-levers, substantially as set forth.

3. The combination, in a bolt-cutter, of the 35 cutting-jaws pivoted in straps upon each side thereof, operating-lever handles pivoted to the cutting-levers, and the adjusting-blocks adapted to be placed in the joint between the lever-handles, substantially as set forth.

4. The combination, in a bolt-cutter, of the 40 cutting-levers pivoted in straps engaging upon either side thereof adjacent to the cutting-edges, the semicircular recesses in each cutting-lever substantially in line between 45 the pivoted point of the jaws, the bearing-pin engaging in the semicircular recesses and adapted to prevent lateral movement of the cutting-levers with reference to each other, the lever-handles pivoted to each other and 50 to the cutting-jaws, and the adjusting-block adapted to be inserted in the joint between the lever-handles, substantially as set forth.

5. The combination, in a bolt-cutter, of the 55 cutting-levers pivoted in straps engaging upon either side thereof adjacent to the cutting-edges, the semicircular recess in each cutting-lever substantially in line between

the pivotal points of the cutting-levers, the bearing-pin in the semicircular recesses to prevent lateral movement of the jaws with 60 reference to each other, the operating-lever handles pivoted to the ends of the cutting-levers and to each other, the adjusting-blocks in the joint between the lever-handles, and the projection for preventing the rotation of the 65 adjusting-block, substantially as set forth.

6. The combination, in a bolt-cutter, of the cutting-levers pivoted in straps engaging upon either side thereof adjacent to the cutting-edges, the semicircular recesses in each 70 of the cutting-levers substantially in line between the pivotal points thereof, the bearing-pin within the semicircular recesses, the lever-handles pivoted to each other and to the ends of the cutting-levers, the adjusting-block 75 adapted to be used in the joint between the lever-handles, and the adjustable buffer upon the lever-handle, substantially as set forth.

7. The combination, in a bolt-cutter, of the cutting-levers pivoted in straps, the semicircular recesses in each cutting-lever substantially 80 in line between the pivotal points thereof, the bearing-pin within the semicircular recesses and adapted to prevent lateral movement of the cutting-levers with reference to 85 each other, the operating-handles pivoted to the cutting-levers and to each other, the adjusting-blocks adapted to be inserted in the joint between the operating-lever handles, and the protecting-washer over the joint between 90 the operating-lever handles, substantially as set forth.

8. The combination, in a bolt-cutter, of the cutting-levers pivoted in straps engaging upon either side thereof adjacent to the cutting-edges, the semicircular recess in each of the cutting-levers substantially in line between the pivotal points, the bearing-pin within the circular recesses adapted to prevent lateral movement of the jaws with reference to each other, the lever-handles pivoted to the cutting-levers and to each other, the adjusting-blocks adapted to be inserted in the 100 pivotal joint between the operating-levers, the protecting-washer over the joint between 105 the pivotal levers, and the adjustable buffer in the operating-lever handles, substantially as set forth.

In witness whereof I have affixed my signature in presence of two witnesses.

WILLIAM L. DUTCHER.
